The ornamental design for a decorative bat with lights, as shown and described.

DESCRIPTION

FIG. 1 is a top perspective view of a decorative bat with lights design showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion “9” in FIG. 1; and,

FIG. 10 is an enlarged view of the selected portion “10” in FIG. 2.

Any shading and cross-hatching are not features of the design but are utilized to illustrate the surface contours of the decorative bat with lights design in the drawings. The broken lines in the drawings depict portions of the decorative bat with lights that form no part of the claimed design.
